(57) CLAIM

The ornamental design for a decorative votive holder, as shown.

DESCRIPTION

FIG. 1 is a perspective view of a decorative votive holder;
FIG. 2 is a front view thereof;

FIG. 3 is a back view thereof;

FIG. 4 is a side view thereof;

FIG. 5 is a top view thereof; and,

FIG. 6 is a bottom view thereof.

In the drawings, the broken lines shown in FIGS. 2, 3 and 4 depict environmental subject matter only and form no part of the claimed design.
